CLAIM

The ornamental design for a TV receiver, as shown and described.

DESCRIPTION

FIG. 1 is a front, right side, perspective view of a TV receiver showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view thereof;

FIG. 9 is an exploded perspective view thereof;

FIG. 10 is an enlarged view thereof; and,

FIG. 11 is an enlarged view.

The broken line consisting of unevenly sized dashes defines reference to the enlargements shown in the figures and form no part of the claim; while all other broken lines in the drawings depict portions of the TV receiver that form no part of the claimed design.

The unshaded surfaces shown between the solid lines and the broken lines form no part of the claimed design.
